UNITED STATES PATENT OFFICE.

GEORGE F. DUTCH, OF NEW YORK, N. Y.

IMPROVEMENT IN POCKET CARTRIDGE-LOADERS.

Specification forming part of Letters Patent No. 130,414, dated August 13, 1872.

SPECIFICATION:

I, G. F. DUTCH, of the city of New York, in the county and State of New York, have invented certain Improvements in Instruments for Reloading Cartridge-Shells for Breech-Loading Fowling-Pieces, &c., of which the following is a specification:

Object and Nature of the Invention.

This invention relates to those instruments which are used for extracting the exploded cap from metallic or other cartridge-shells for breech-loading fowling-pieces, and for recapping and reloading said shells, so as to use them a second, third, or more times. I am aware that machines have been made for such purposes, but such machines have levers or screws acting upon separate plungers. I know that simple "loaders" or plungers having a handle have been made to serve the double purpose of a loader and cap-extractor, but not a recapper. The object in view is to obtain a pocket instrument cheap to manufacture, simple, and durable, which will combine the three into one instrument—viz., cap-extractor, recapper, and loader. The invention consists in the combination of a plunger with a head or thimble-knob, whereby the object is attained.

My improved reloader I construct as follows:

Description of Drawing.

Figure 1 is a longitudinal section through center of my universal reloader, as it is when closed to put in the pocket, or to be used as recapper and reloader. Fig. 2 is a similar view of the same, represented in the position for extracting the exploded cap of a shell; and Fig. 3 is again a similar view of the same in position in the shell for recapping said shell.

General Description.

C is a plunger, the body of which is cylindrical, and the two ends of which are shaped as seen in the drawing, as follows: The end D is turned down smaller for a certain distance leaving a small shoulder; this turning down the end is to enable said end to enter the re-enforced part of the shell, so as to sustain in a central position the pin E, which is inserted firmly in a cavity made at the center of the end D of the plunger C. The end F of the plunger C has also a cavity, G, at its center, so as not to allow the plunger's end to

come in contact with the cap-holder or chamber, while the flat part of the end F will fit and rest upon the annular space left all around the said cap-holder at the butt of the cartridge. A is a head or knob, fitting over the part D of the plunger C, as seen in the drawing, and having an annular space, B, turned at the top, so as to receive the flange end of the cartridge-shell. The shape of the balance of the head A is entirely optional with the manufacturer, but in order to render it neat and handy I prefer it of the knob-shape illustrated in my drawing. Both the plunger C and head A may be made of metal, ivory, bone, wood, rubber, horn, &c.; and the pin E is made of metal.

Operation of my Improved Loader.

When the head A is placed on the end d of the plunger C the pin E is protected, and my instrument may be packed with the gun or carried in the pocket. It is a good loader, and is also ready to be used for recapping, as seen in Fig. 3, where the end F of the plunger C is introduced into the shell L, and the plunger pushed down as far as it will go therein. A percussion-cap is now placed at J, and is resting against or on a solid surface, x, when a slight blow with the hand upon the head A will drive the cap home perfectly safe and straight without spoiling the shell, for the end of the plunger F bears fair upon the butt K of the said shell. For extracting the exploded cap of a shell take off the head A from the plunger C, uncovering the pin H; slip the cartridge over the end D of the plunger C; place the whole (resting the end F) against or upon a solid surface, Z; place the head A over the butt of the cartridge, as seen in Fig. 2, when a small tap with the hand upon the top of the head A will drive out the cap from the cap-holding cup H.

What I claim as my invention, and desire to secure by Letters Patent of the United States, is—

Claim.

The combination of the plunger C and head A, constructed substantially as described, to make a combined pocket cartridge-shell, reloader, recapper, and cap-extractor, as herein set forth.

GEO. F. DUTCH.
